CLAIM

The ornamental design for a capacitor, as shown and described.

DESCRIPTION

FIG. 1 is a perspective view of a capacitor showing my new design;

FIG. 2 is a front view of the capacitor shown in FIG. 1;

FIG. 3 is a rear view of the capacitor shown in FIG. 1;

FIG. 4 is a left view of the capacitor shown in FIG. 1;

FIG. 5 is a right view of the capacitor shown in FIG. 1;

FIG. 6 is a top view of the capacitor shown in FIG. 1; and,

FIG. 7 is a bottom view of the capacitor shown in FIG. 1.

The broken lines in the drawings are included to show unclaimed subject matter only and form no part of the claimed design.
